UNITED STATES PATENT OFFICE

HUBERT M. WHITAKER, OF ENFIELD, NORTH CAROLINA

SIGNAL SWITCH

Application filed July 24, 1925. Serial No. 45,910.

This invention aims to provide novel means whereby the operator of a motion picture machine may be advised when the roll is nearly run off the machine.

5 It is within the province of the disclosure to improve generally and to enhance the utility of devices of that type to which the invention appertains.

With the foregoing and other objects in view which will appear as the description proceeds, the invention resides in the combination and arrangement of parts and in the details of construction hereinafter described and claimed, it being understood that 15 changes in the precise embodiment of the invention herein disclosed, may be made within the scope of what is claimed, without departing from the spirit of the invention.

In the accompanying drawings:—

20 Figure 1 is a vertical section showing a device constructed in accordance with the invention, parts being in elevation; Figure 2 is a view similar to Figure 1 but showing a slight modification.

25 In Figure 1, the numeral 1 marks the film magazine of a motion picture machine, the shaft 2 being supported for rotation within the magazine 1 and carrying the film roll 3. A fulcrum block 4 is located inside the 30 magazine 1, and an angle bracket 5 is located outside the magazine, a securing element 6 passing through the wall of the magazine, and connecting both the block 4 and the bracket 5 to the magazine. A lever 7 is 35 mounted at 8 for swinging movement on the fulcrum block 4 and carries a wheel 10 or other anti-friction device adapted to travel on the film roll 3. A switch arm 11 is pivoted at 9 to the lever 7 intermediate the ends of the 40 lever, the switch arm extending outwardly through an opening 12 in the magazine 1. A foot piece 14 of insulating material is attached by securing devices 15 to the outer end of the switch arm 11 and carries a contact 45 terminal 16 adapted to slide along an insulating block 18 and to engage with a terminal 17 on the block 18, the block 18 being united by a connecting device 19, such as a screw, with an angle bracket 20 attached at 21 to the 50 magazine 1, having an elongated slot 22, re-

ceiving the clamping device 19, and permitting a shifting of the block 18 and the contact terminal 17 with respect to the contact terminal 16.

Any suitable means may be provided for holding the contact terminal 16 yieldably on the block 18 for engagement with the terminal 17. If desired, a plunger 23 may be loosely mounted in the bracket 5, the plunger being provided at its inner end with a head 24 bearing on the switch arm 11, a compression spring 25 surrounding a portion of the plunger, one end of the spring bearing on the head 24, and the other end of the spring bearing on the bracket 5. Inward movement of the plunger 23 is limited by a wing nut 26 threaded on the plunger and bearing against a curved washer 27 mounted to rock on the bracket 5.

The electric mains are denoted by the numeral 28 and are connected with the terminals 16 and 17, respectively, by conductors 29 and 30. A signal 31 is interposed in one of the conductors, in the conductor 30, in the present instance. The signal 31 may be a lamp or other kind of a signal, either visible or audible.

As the film is run off the reel, the lever 7 swings downwardly, the wheel 10 traveling on the film roll 3, the arm 11 being carried downwardly, and the contact 16 coming into electrical engagement with the contact 17. When the contacts 16 and 17 are in engagement, the signal circuit is closed, and the signal 31 is operated, thereby admonishing the operator that the film roll is almost run off. As soon as the contact terminal 16 moves downwardly out of engagement with the contact terminal 17, the signal circuit is opened and the signal 31 no longer operates, the operator being then advised that the machine needs immediate attention.

In Figure 2 of the drawings, parts hereinbefore described have been designated by numerals previously used, with the suffix "a". In Figure 2, the magazine 1^a is of rectangular form, whereas the magazine 1 of Figure 1 is of cylindrical outline. The modifications in Figure 2 are few and simple. The lever 7 is shown curved in Figure 1, and

straight in Figure 2, the angle bracket 5^a is changed slightly from the showing of the angle bracket 5, and the same observation holds true with respect to the angle bracket 20^a. The operation of the device depicted in Figure 2 does not differ from the operation of the form shown in Figure 1.

What is claimed is:—

In a device of the class described, a magazine having an opening, a fulcrum block located inside the magazine, an angle bracket located outside the magazine, a securing element passing through the wall of the magazine and engaging the fulcrum block and one leg of the angle bracket to bind the angle bracket and the fulcrum block on the wall of the magazine, a lever within the magazine, one end of the lever being pivoted to the fulcrum block, and the other end of the lever having means for riding on a roll of film within the casing, switch mechanism comprising an arm pivoted to the intermediate portion of the lever and extended out of the magazine through the opening, a plunger slidably mounted in the other leg of the angle bracket and having a head which bears against the arm, and a compression spring surrounding the plunger, one end of the spring exerting a thrust against the head, and the opposite end of the spring exerting a thrust against said other leg of the angle bracket.

In testimony that I claim the foregoing as my own, I have hereto affixed my signature.

HUBERT M. WHITAKER.
